INVENTOR

BY *Victor J. Evans*

ATTORNEY

UNITED STATES PATENT OFFICE

JOHN BESS, OF EL PASO, TEXAS

NOZZLE

Application filed July 2, 1927. Serial No. 203,177.

This invention relates to improvements in nozzles and has for an object the provision of a nozzle which is especially adapted for cleaning locomotive and other boilers.

5 In the ordinary method of cleaning boilers it is necessary that the workmen be positioned substantially beneath the boiler opening and the workmen are thus in the path of the water which runs out of this opening. 10 The workmen are frequently burned or scalded in this position, and their clothes quickly become wet, with the result that many workmen contract serious illnesses.

It is therefore the primary object of the 15 invention to provide a clean-out nozzle whose adjustment is such that access may be conveniently had to all parts of the boiler without danger of burning or scalding the workman, the character of the invention being 20 such that the workman is not required to get beneath the boiler shell, but may stand to one side while the boiler is being cleaned.

A further object of the invention is the 25 provision of a nozzle for the above purpose which will save time, labor and expense due to the frequent replacing of wash-out plugs and the deterioration of the front ends of the boiler.

With the above and other objects in view, 30 the invention further includes the following novel features and details of construction, to be hereinafter more fully described, illustrated in the accompanying drawings and pointed out in the appended claims.

35 In the drawings:—

Figure 1 is an elevation of the invention.

Figure 2 is an elevation at right angles to Figure 1.

Figure 3 is a top plan view.

40 Referring to the drawings in detail where in like characters of reference denote corresponding parts, the reference character 10 indicates a pipe which is adapted to supply water to the nozzle 11. This nozzle has its 45 orifice disposed axially at the end of the nozzle and is adapted for insertion through any one of the openings in the boiler after the plugs have been removed. The nozzle is capable of being adjusted to direct water to 50 different parts of the water space, such as

the throat sheet, crown sheet, or other ordinarily inaccessible spaces.

To accomplish this, the pipe 10 has extending therefrom, a rightangled portion or elbow 10^a, which is connected to the nozzle by means of a swiveled joint 12, with which the stem of the nozzle is in axial alinement. The nozzle may be arranged vertically so as to direct the spray forwardly or laterally, or the nozzle may be arranged horizontally and the 60 spray directed either upward or downward. By this means the spray will reach into all parts of the boiler and the latter may be thoroughly cleaned.

For the purpose of manipulating the nozzle, the latter has connected thereto an arm 13 which extends at right angles from the nozzle stem, and pivotally connected to this arm is one end of a rod 14, the said rod being 65 preferably provided with a ring or loop 15 at its opposite end to provide a handle or grip. Thus, the nozzle may be inserted through any of the wash-out openings after the plugs have 70 been removed, and the nozzle may be rotated through the medium of the rod 14 with the operator remaining a sufficient distance away from the opening to prevent burning or scalding, or wetting.

The arm 13 is carried by a collar 13^a and the latter is secured to the nozzle by means 75 of a set screw 13^b. Thus the arm may be adjustably positioned with respect to the curved discharge end of the nozzle to suit various conditions and to facilitate manipulation of the nozzle.

80 The invention is susceptible of various changes in its form, proportions and minor details of construction and the right is herein reserved to make such changes as properly fall within the scope of the appended claims.

85 Having described the invention what is claimed is:—

1. A clean out nozzle for boilers comprising in combination, a supply pipe having a right-angled extension at one end, a substantially L-shaped nozzle adapted for removable insertion through the clean out opening of a boiler and having a relatively long stem arranged in axial alinement with the outer end of the right angled extension, a swivel con- 95

- nection between said extension and stem whereby said stem may be rotated axially with respect to the rightangled extension of the supply pipe, an arm having one end secured to the stem of the nozzle and extending at a right angle to said stem, and an operating rod having one end pivotally connected to the outer end of the arm to adjust the position of the discharge end of the nozzle.
- 10 2. A clean out nozzle for boilers comprising in combination, a supply pipe having a right angled extension at one end, a substantially L-shaped nozzle adapted for insertion through the clean out opening of a boiler and having a relatively long stem arranged in axial alinement with the outer end of the right angled extension and a relatively short right angled discharge end with its discharge orifice disposed at a right angle with respect
- 15 to the stem, a swivel connection between said extension and stem with the extension in axial alinement with the stem, whereby said stem may be rotated axially with respect to the rightangled extension of the supply pipe.
- 20 3. An arm having one end secured to the stem of the nozzle and extending at a right angle to said stem, and an operating rod having one end pivotally connected to the outer end of the arm to adjust the position of the discharge end of the nozzle and means to secure the arm to the stem to permit of rotary adjustment of said arm upon said stem.

In testimony whereof I affix my signature.
JOHN BESS.
